FLUORESCENT TUBULAR LAMP

Filed Aug. 15, 1940

UNITED STATES PATENT OFFICE

2,305,721

FLUORESCENT TUBULAR LAMP

John F. Livers, Decatur, Ill., assignor to Farles Manufacturing Company, Decatur, Ill., a corporation of Illinois

Application August 15, 1940, Serial No. 352,731

4 Claims. (Cl. 240—81)

My invention relates to lamps which employ the fluorescent light source. Lamps of this type with which I am familiar are subject to one or more of the following objections.

Many of them concentrate the light rays emitted by the fluorescent tube in an area adjacent to the axis of the tube with the result that that portion of the desk used for work has a much lower candle power, causing a very unsatisfactory working condition. Attempts to remedy have been made by attempting to project the light rays onto that part of the desk. This however, results in causing veiling glare with its grave objections. Especially is this the case if the fluorescent tube is exposed without any protective means.

My invention has for its principal object to overcome these objectionable features peculiar to fluorescent lighting by combining two types of reflectors which partially surround the light source and associating them with one or more louvers or screens, which are rotatably mounted, so that it is possible to redirect the rays as desired.

A further object is to provide for mounting the entire reflecting assembly and its housing so that its position can be varied so as to distribute the light rays to meet various conditions such as dimensions of the areas to be illuminated, sensitiveness of the eyes of a user or his stature.

A further object is to provide means for detachably mounting the louvers so that they may be easily and quickly removed, thus affording easy access to the lamp either to clean or replace it or to clean the reflecting surfaces.

A further object is to mount the lamp so that a portion of it will project below the lip of the reflector.

My means of accomplishing the foregoing objects may be more readily understood by reference to the accompanying drawing which is hereto annexed and forms a part of this specification in which:

Fig. 1 is a front elevation of my device;

Fig. 2 is a cross section on line 2—2, Fig. 1, looking in direction of the arrow;

Fig. 3 is a fragmentary detail view of a raceway.

Similar reference numerals refer to similar parts throughout the entire specification.

As shown in the drawing, my lamp has a base 10, which obviously may be of any desired contour. A pair of standards 12 and 14, extend upwardly from the base 10. Secured to the top of the standards 12 and 14, is a reflector housing

16, which is secured by means of adjustable joints 18.

The housing is formed with a vertical rear wall 20, a horizontal top wall 22, and a forwardly projecting extension 24, which is inclined downwardly and has a plane surface the inner side of which is finished with a diffuse reflecting coating such as baked white enamel. The ends of the housing 16 are closed by end walls 26 and 28.

Adjacent each end of the housing 16 I mount the sockets 29 and 30, to support the ends of the fluorescent tube 32, which forms the light source for the lamp. Above and partially surrounding the light source 32, I mount a reflector 34, the inner surface of which is coated with any suitable specular reflecting medium.

In practice I have found it satisfactory to form this reflector 34 of "Alzak" processed aluminum. Preferably the upper front edge 36, of this reflector 34, should terminate adjacent the beginning of the diffuse reflecting medium on the extension 24, of the reflector housing 16.

On each of the end walls 26 and 28, I mount raceways 37 and 38, respectively. These raceways are adapted to receive the ends 40, of two flat louvers 42 and 44, one side 46, of which is coated with a reflecting medium, the other side 48, being coated with a mat black coating. These louvers 42 and 44, are rotatable in their respective raceways 37 and 38. A convenient way to remove them for cleaning them or the reflectors, or to change the light source, is afforded by means of slots 50 and 52.

It will be clear to persons skilled in the art that in this way I provide for quick and easy adjustment of these louvers so as to direct the light rays emitted by the light source 32. Also that by means of the adjusting nuts 18, the entire housing assembly may be shifted in order to obtain different distribution of the light flux as may be desired or required, for portable or clamp type desk or floor lamp.

Having described my invention, what I regard as new and desire to secure by Letters Patent is:

1. A portable lamp comprising a fluorescent light source, a specular reflector above and partially surrounding said light source, said reflector extending longitudinally of the light source and parallel thereto, a reflector housing above said light source having a forwardly projecting extension which extends beyond the front edge of the reflector, the edge of which is on a horizontal plane passing through the axis of the light source, said extension being coated with a diffuse reflecting medium, end portions for said

housing, raceways secured to the inner surface of said end portions, a pair of louvers the ends of which are rotatably mounted in said raceways, one side of each of said louvers being a reflector the other side having a dull black coating, said raceways being located below the axis of the light source and between it and the edge of the housing.

2. A portable lamp comprising a fluorescent light source, a specular reflector mounted above and longitudinally thereto, said reflector partially surrounding the light source and being parallel to it, a reflector housing which partially enclosed said reflector, a forwardly projecting extension on said housing, which extends beyond the front edge of the reflector and projects in a slanting direction until its edge intersects a horizontal plane passing through the axis of the light source, said extension having its inner surface coated with a diffuse reflecting medium, a pair of louvers adapted to be manually adjusted and partially eclipse said light source, one side of said louvers being coated with a reflecting medium, the other being coated with a dull black finish, and raceways on said housing in which are rotatably mounted the ends of said louver, said louvers being mounted in staggered relation below the axis of the light source and between it and the edge of the forwardly projecting portion of the housing.

3. A portable lamp comprising a fluorescent light source, a specular reflector mounted above and longitudinally thereto, said reflector partially surrounding the light source and being parallel to it, a reflector housing which partially

5 encloses said reflector, a forwardly projecting extension on said housing, which extends beyond the front edge of the reflector and projects in a slanting direction until its edge intersects a horizontal plane passing through the axis of the light source, said extension having its inner surface coated with a diffuse reflecting medium, a pair of louvers adapted to be manually adjusted and partially eclipse said light source, one side of said louvers being coated with a reflecting medium, the other being coated with a dull black finish, and raceways on said housing in which are rotatably mounted the ends of said louvers, said louvers being mounted in staggered relation below the axis of the light source, and between it and the edge of the forwardly projecting portion of the housing, there being means to detachably mount said louvers in said raceways.

10 20 4. A desk lamp comprising a fluorescent light source, a specular reflector above and partially surrounding said light source, said reflector extending longitudinally of the light source and parallel thereto, a diffusing member projecting forwardly from the front edge of the reflector and extending to a horizontal plane passing through the longitudinal axis of said light source, end portions for said reflector, raceways secured to the inner surface of said end portions, and louvers having their ends rotatably and removably mounted in said raceways; said louvers being located below a plane passing through the axis of the light source and the front edge of said diffusing member.
